UNITED STATES PATENT OFFICE.

GEORGE W. BOSTWICK, OF SACRAMENTO, CALIFORNIA.

WALL CONSTRUCTION.

1,189,189.

Specification of Letters Patent. Patented June 27, 1916.

Application filed April 9, 1915. Serial No. 20,260.

To all whom it may concern:

Be it known that I, GEORGE W. BOSTWICK, a citizen of the United States of America, residing at Sacramento, in the county of Sacramento and State of California, have invented new and useful Improvements in Wall Construction, of which the following is a specification.

This invention relates to improvements in brick and stone wall construction and the method of erecting the same.

In carrying out the present invention, it is my purpose to form brick, stone and analogous building elements in such manner that walls may be erected by any one skilled or not skilled in the art of brick laying, thereby reducing the cost of the labor.

It is also my purpose to form the brick and stone in such manner that after the wall is erected the mortar and other filling material will be invisible from the front and back of the wall, while the front or face of the wall will have the appearance of the usual brick or stone wall.

A further object of my invention is to provide a method of erecting walls whereby the brick or stone may be readily assembled in wall formation and the mortar or other filling material poured into the space between the face and back of the wall so that such filling material will enter the crevices between the bricks or stone and act to hold the latter rigidly and securely in wall formation.

With the above and other objects in view, the invention consists in the construction, combination and arrangement of parts hereinafter set forth in and falling within the scope of the claims.

In the accompanying drawings; Figure 1 is a view in front elevation of a wall constructed in accordance with the present invention. Fig. 2 is a vertical transverse sectional view therethrough. Fig. 3 is a view similar to Fig. 2 of the wall as having a stone face and a back of brick. Fig. 4 is a face view of a wall constructed of common brick. Fig. 5 is a vertical transverse sectional view through the wall shown in Fig. 4. Fig. 6 is a view similar to Fig. 5 showing the wall as reinforced.

In Figs. 1 and 2 of the drawings I have shown a wall formed of bricks, joint strips and filler blocks constructed in accordance with the present invention, such wall having the front side formed of face brick and the rear side formed of brick. In erecting the

wall a foundation or base of cement or other material is formed. The face brick are now arranged upon the base and disposed in rows one upon the other and the bricks in each row are arranged end to end, and edge to edge with the bricks in adjacent rows, and interposed between the backs 2 of the bricks in adjacent rows are the backs 11 of the horizontal joint strips while the faces 12 of such strips are disposed between the confronting edges of the rows of bricks and set inwardly of the outer surfaces of the faces 1 of the bricks, as clearly illustrated in Figs. 1 and 2 of the drawings. The backs 2 and 11 of the face bricks and the horizontal joint strips are held properly spaced apart by means of spacing blocks 16' that are interposed between the confronting surfaces of such backs. Disposed between the confronting ends of the bricks in each row are the vertical joint strips, the backs 17 of the vertical joint strips being interposed between the ends of the backs of the face bricks, while the face strips 18 of the vertical joint strips are disposed between the confronting ends of the faces 2 of the face bricks, as clearly shown in Fig. 1 of the drawings. The back of the wall shown in Figs. 1 and 2 is formed by common brick and these bricks are arranged in rows and the bricks in each row are placed in end to end contact with one another and in edge to edge contact with the bricks of adjoining rows and the rows of common brick alternate with the rows of face brick, as shown in Fig. 2, the inner ends of the backs of the common bricks facing the adjacent ends of the horizontal joint strips. Interposed between the backs of the rows of bricks are the filler blocks and the tops and bottoms of the filler blocks 16 are adjacent to the tops and bottoms of the rear portions of the backs 2 of the face bricks, as illustrated in Fig. 2 of the drawings. The filler blocks and the backs of the common bricks are held properly spaced apart by means of spacing blocks 16' corresponding to the filler blocks 16. During the course of construction of the wall, a cementitious substance is poured into the crevices between the bricks, joint strips and filler blocks after the erection of predetermined numbers of rows of bricks and when the wall has reached the required height and the cementitious substance in the crevices hardened, the bricks, joint strips and filler blocks are bound together, while a casual observa-

tion of the front of the wall gives the impression of an ordinary brick wall, the faces of the face bricks simulating other styles of face bricks, while the face strips 12 and 18 of the horizontal joint strips and vertical joint strips respectively simulate mortar.

In Fig. 3 of the drawings, I have shown the face of the wall as composed of stone in contradistinction to the brick face illustrated in Figs. 1 and 2 of the drawings and the backs of the common bricks and the filler blocks are spaced apart from the backs of the stones and joint strips.

In Figs. 4 and 5, I have shown the front of the wall as formed of common brick as contradistinguished from face brick and when both faces of the wall are formed of common brick the horizontal joint strips and the vertical joint strips are eliminated and the method of construction carried out the same as in Figs. 1, 2 and 3.

The wall shown in Fig. 6 is substantially the same in construction as that illustrated in Figs. 4 and 5, but in the construction shown in Fig. 6 the inner ends of the bricks and filler blocks forming the front and back respectively of the wall are spaced apart a greater distance than the similar bricks and filler blocks in Figs. 4 and 5 and this space is filled by a cementitious substance and this cementitious substance is reinforced by metal wall ties as shown so as to reinforce and strengthen the wall.

It will be understood, of course, that in the construction of a wall rows of header bricks are interposed between the rows of stretcher bricks at predetermined points so as to strengthen the structure.

While the brick or stone joint strips and filler blocks in the wall as herein described are spaced apart by the spacing blocks 16', I do not wish to be confined to the use of such spacing blocks only, as in many cases it may be preferable to place ordinary mortar on the various shelves and filler blocks, such mortar acting as a spacing agent.

While I have herein shown and described certain preferred forms of my invention by way of illustration, I wish it to be understood that I do not limit or confine myself to the precise details of construction herein described and delineated, as modification and variation may be made within the scope of the claims without departing from the spirit of the invention.

Wherever, in the specification, I have referred to common brick, I mean brick formed of ordinary clay, etc., in contradistinction to face brick or other fancy brick.

I claim:

1. In wall construction, rows of bricks superimposed one upon another, each brick having a wide face and a relatively narrow back, the bricks in each row being placed end to end with one another and edge to edge with the bricks of adjoining rows, joint strips having wide backs and relatively narrow face strips, the backs of said joint strips being interposed between the backs of the bricks and the face strips being disposed between and in contact with the edge faces of the bricks, and a cementitious substance filling the space between the bricks.

2. In wall construction, rows of bricks superimposed one upon another, each brick having a wide face and a relatively narrow back, the bricks in each row being placed end to end with one another and edge to edge with the bricks of adjoining rows, filler blocks interposed between the backs of the bricks, a cementitious substance filling the space between the bricks, and spacing blocks interposed between the confronting surfaces of the filler blocks and the backs of the bricks.

In testimony whereof I affix my signature in presence of two witnesses.

GEORGE W. BOSTWICK.

Witnesses:

CHESTER H. CARMICHAEL,
MICHAEL J. CLAUGHERTY.
